FILTER SYSTEM

Otto Murray Summers, Glasgow, Ky., assignor to
 The Thompson Grinder Company, Springfield,
 Ohio, a corporation of Ohio

Application February 13, 1946, Serial No. 647,245

8 Claims. (Cl. 210—150)

1

The present invention relates to structure for filtering lubricating fluids, particularly those which are used in connection with the various machines such as grinders, lathes, etc.

In the case of grinding machines, it is customary to use a combined coolant and lubricating fluid at the work surface of the grinding wheel in order to facilitate the abrasive action, to eliminate sparks, etc. This fluid is pumped against the grinding wheel so as to flow onto the work surface and the fluid then finds its way, usually by gravitation, to a reservoir from which the fluid is again re-circulated. The fine abrasive powder which is obtained in part from the grinding wheel and also, in part from the work piece is carried by the coolant to the reservoir where it is permitted to settle out of solution and the pump draws from a region in which the liquid is fairly clear. It is obvious that an arrangement of this character may work satisfactorily in case the metal particles or pieces are of such size as to drop quickly by gravity into the settling tank so as effectively to remove themselves from the circulating fluid. However, in certain types of grinders, particularly those of high precision, extremely fine cuts are made on the work piece and the metal particles may be of microscopic size so that they go into suspension in the coolant fluid. The settling method of separating the solid material from the liquid would not be altogether satisfactory in cases of this kind because the fluid, when being returned by the pump to the grinding position, would contain certain amounts of metal particles which may greatly affect the accuracy of grinding and the character of the ground surface.

The primary object of the invention is to provide a filtering apparatus which is readily adaptable to fine cut, high precision grinding machines and in which the microscopically small particles are completely removed from the coolant at the time it is received by the pump in order to be fed to the grinding position.

Another object is to provide a machine of the character described in which the solid particles, regardless of their diminutiveness, are separated from the coolant fluid and are ejected from the machine as a mass so as to be removed from the circulating fluid.

Still another object is to provide filtering apparatus adapted for use in abrasive machines and in which no settling reservoir is necessary, but the filtering action is performed by elements contained in the fluid system.

Another object is to provide an improved ap-

paratus for finely separating solid particles of microscopic or other size from the fluid in which they are contained, said apparatus also serving to present the fluid from which the particles had been removed to a working surface.

A still further object is to provide apparatus of the character described in which the filtering or separating function can be carried to any degree of fineness by adding filtering or separation devices in order that the extreme degree of purity of the coolant is obtained so as to improve the cutting or abrasive action of the working tool on the work piece.

The above objects are attained in brief by employing structure consisting of one or more specially designed filtering units, connected in series and preferably of different coarseness, together with a provision for applying the force of gravity in the separation of the solid particles from the fluid which are then expelled from the reservoir.

Other features and objects will be apparent as the specification is perused in connection with the accompanying drawings in which:

25 Figure 1 represents a perspective view in a somewhat diagrammatic form of a grinder which is provided with the improved filtering or particle separating unit.

Figure 2 is a sectional view taken along line 30 2—2 in Figure 1 and showing in elevation the centrifugal pumps and their actuating motor for circulating the particle containing fluid through the filter structure.

Figure 3 is a longitudinal sectional view of the filtering unit and tank taken along line 3—3 in 35 Figure 1.

Figure 4 is a sectional view somewhat enlarged, taken along line 4—4 in Figure 3 across one of the filtering elements.

Figure 5 is a longitudinal sectional view of the 40 sludge or swarf pump for removing any settling from the filter units.

Figure 6 is a fragmentary sectional end view of the pump shown in Figure 5, but in which the 45 pistons are illustrated as having been moved to their retracted respective positions.

Figure 7 is a plan view of the star valve taken along line 7—7 in Figure 6 and in which the valve is positioned in line with the respective pistons of the pump.

Figure 8 is an enlarged sectional view taken along line 8—8 in Figure 3 and showing the second filter element of the system.

Figure 9 represents a mid-section view of the 50 filter unit shown in Figure 8, but of somewhat

smaller size and in which the filter unit has been collapsed preparatory to receiving a charge of the particle-containing coolant.

Figure 10 is a plan view looking down on top of the filter compartments, but with the top of each compartment removed so as to expose the entire elements.

Figure 11 is an enlarged fragmentary view of the device in sections for holding the filter bags in place.

Figure 12 is a view, greatly enlarged, of a small piece of the fabric used for the filters and indicating the manner in which the filtering or sediment-separating function takes place.

Referring more particularly to Figures 1 and 2, reference character 1 designates generally a grinding machine which is formed of a large base 2 containing the actuating apparatus, motors, gears, etc., for reciprocating a table 3 longitudinally of the base. A guard 4 is provided at the end of the reciprocatory table and if desired, a stationary platform or ledge 5 may also be secured to the base for supporting work pieces. The base 2 is provided at one end with a rearwardly and upwardly extending frame 6 to which a pair of vertical supports 7 may be secured. The top of the frame 6 carries a large inverted shield 8 which extends over a horizontally disposed grinding wheel 9 suitably journaled as indicated at 10 from a sub-frame 11. The latter is supported in any suitable manner on a member 12 carried by the uprights 7. The base 2 also serves as a support for a vertically extending plate 13 which is positioned at the rear end of the travelling table or carriage 3 which serves as a guard against sparks moving toward the rear of the machine. A motor 14 which is carried by the member 12 serves to rotate the grinding wheel 9 at a fast rate of speed. It will be understood that suitable mechanism is provided, manually or automatically controlled, for moving the grinding wheel 9 in a transverse direction so that a work piece placed on the travelling table 3 can be ground to any desired size or shape.

It has been customary to apply a coolant to the grinding wheel 9, this fluid serving to reduce the temperature at the abraded surface as well as to reduce the sparking effects. The coolant is usually supplied, through a pipe or conduit 15 to a suitably shaped nozzle 16 positioned at a convenient place near the grinding wheel. The coolant, after being emitted at the nozzle, flows by gravity onto the table 3, then through an elongated trough 17 extending along the rear edge of the table (Figure 2) into a U-shaped compartment 18 formed in the base 2. From this compartment the coolant is usually run into a reservoir (not shown) and there allowed to remain throughout a settling period during which the metal particles tend to separate out of solution and thus drop into the bottom of the reservoir. A pump takes the coolant from which the particles have separated and forces the coolant through a flexible pipe 19 to a stationary conduit 20 which is connected to the conduit 15. A structure of this general character has been more or less satisfactory in cases where the grinding is of a rough type so that the particles are quite coarse or large, and therefore tend to settle in the reservoir rather quickly. However, in the case of precision grinding in which only extremely small cuts are taken at any one time and the particles are therefore microscopically small, it is found that such particles go into solution with the coolant and remain for the most part sus-

pended in the liquid. In the case of prior art machines, the fluid pump would, therefore, force this particle-containing fluid into the nozzle 16 and these particles would generally interfere with the grinding operation, either by way of making the depth of cut inaccurate or bumpy or else by spoiling the character of the surface.

In accordance with one of the aspects of my invention, an improved filter structure and system has been provided by which practically all of the particles, regardless of size, microscopic or larger, are completely removed from the coolant.

The improved filter is conveniently housed in a chamber 21, preferably of rectangular shape and may be formed of heavy sheet metal or cast as a member integral with the body 2. The sides of the chamber or compartment 21 are indicated at 22, 23 (Figure 3) and 24 (Figure 1). The top and bottom closures of the box are indicated at 25 and 26 respectively. There is a pair of spaced partitions 27, 28 extending transversely across the box preferably made of heavy sheet metal so as to divide the box or compartment 21 into three sections indicated generally at 29, 30 and 31 respectively (Figure 3).

The first section 29 includes a pair of vertically mounted superposed centrifugal pumps 32, 33 and electric motor 34 for driving the pumps. For supporting these elements within the compartment, a pair of transversely extending webs 35, 36 is employed. These webs have an opening for receiving a conically shaped housing 37 which carries the pumps 32, 33. The housing may be supported from plates 38, bolted or otherwise secured to the webs 35, 36. The motor 34 is also contained within a housing 39 and the latter is supported in any suitable manner from the upper plate 38. A shaft 40 is suitably journaled within the housing 37 and also at the plates 38, this shaft carrying at an intermediate and at an end position an impeller contained within the pump casings 32, 33. The upper end of the shaft is suitably connected to the armature or rotor of the motor 34 so that when the latter is actuated, the impellers in the pumps 32 and 33 are rotated at a relatively high speed. The structural arrangement is such that all rotating parts of the pumps 32, 33 and of the motor 34 are rendered fluidtight from the surrounding body of lubricating coolant. The outlet of the pump 32 may comprise a pair of pipe lengths 41 connected together through a coupling 42 and supported in any suitable manner from the upper plate 38. The inlet of the pump 32 constitutes the usual centrally positioned opening indicated at 43 through which coolant contained within the immediately surrounding compartment 29 is permitted to enter the pump and to be forced out through the pipes 41 under pressure.

The lower pump 33 has an inlet and an outlet opening indicated at 43, 44 respectively, the latter being in communication with a pipe 45 which leads to an upright pipe 46 positioned in the last compartment 31 (Figure 3). The outlet conduit 41 of the upper pump 32 communicates with the flexible hose 19 which leads to the nozzle 16 (Figure 1).

The coolant which enters the inlet opening of the pump 32 is contained in the immediately surrounding space in compartment 29 and this compartment is kept full by admitting fluid through an opening 47 in the partition 27. This opening communicates with the exterior surface of a large filter unit generally indicated at 48 con-

tained in the middle compartment 30. The inlet opening of the pump 33 obtains its coolant from the liquid body immediately surrounding the pump in the lowermost compartment 29 and this compartment is maintained full by admitting coolant through a pipe 49 which leads from the rectangularly shaped groove 18 (Figure 2) extending lengthwise of the base 2 at the rear edge thereof.

Filter structure

The filter through which the coolant passes to the inlet of the pump 32 is constituted of a pair of bags 50, 51 spaced apart as shown in Figure 8 and arranged in an inverted position, i. e. the closed ends of the bags are at the bottom of the compartment 30. These bags have cylindrical portions 52, 53 respectively and lower spherical portions 54, 55. The portion 55 of the inner bag 51 may be inwardly joined to the cylindrical portion but the portion 54 of the outer bag is made separate from its cylindrical portion 52 and is attached thereto at the lower edge by means of a heavy metal ring 56 passing around the inner surface of a flanged extension of the portion 54. A series of wire loops or strands 57 serve to hold both thicknesses of the outer bag against the ring 56 as shown in Figure 8. The inner bag 51 is made of light material having a fairly tight weave and serves to filter and remove the scum from the coolant fluid. This inner bag is designed to be replaced daily since practically all of the foreign material in the coolant which reaches this particular filter is caught by this inner filter element. The outer bag 50 is preferably made of fiberglass, canvas or other suitable material, for mechanical strength and for filtering the few particles which have passed through the inner scum bag.

There is provided for holding the bags in a suspended position and properly spaced, a ring 56' having a relatively wide flange 57' which rests on an inwardly extending web 58 secured to the walls of the compartment 30. The ring 56' is provided with a large number of peripherally positioned openings 59 preferably formed by an upsetting operation as indicated at 60. These openings serve as an egress for fluid which may have collected at the top of the bags 50, 51 in case passage through one or both bags is partially stopped. The member 56' is provided at the bottom edge with a narrow ring of metal 61 of substantial thickness and formed by doubling a circular strip of material on itself and secured in any suitable manner to the element 56'. The width of the annular ring 61 corresponds to the thickness of the space between the two bags 50, 51. A clamping ring 62 is fitted against the upper edge of the inner bag 51 and forces this portion of the bag against the metal ring 56' at a position above the annular member 61. Binding wire is wrapped around the upper edge of the outer bag 50 and at a position opposite the retaining ring 62 so that both bags are rigidly secured to the depending ring 56' and thus held in spaced position. At a position approximately midway of the length of the outer bag there is a pair of circular tension springs 63 contacting the outer bag surface and secured thereto by being sewn within a canvas matrix 64 which also serves to position the springs apart. The purpose of these springs will be apparent when the function of the filter has been explained.

In order that the inner light bag 53 may be readily replaced, usually day by day since the

crevices between the threads of the bag tend to fill with scum, a pair of hand operated adjustable clamps generally indicated at 65 is employed, these clamps being placed diametrically opposite one another and so arranged as to detachably hold the flange 57' to the web 58. An enlarged detailed view of these clamps is shown in Figure 11. A thumb screw 66 is threaded through the web 58, this screw being provided with a sleeve 67 which fits somewhat loosely in a rectangular plate member 68 which has a cutaway portion 69. The inner end of the plate 68 is adapted to press against the outer surface of the flange 57' when the thumb screw 66 is tightened so that the latter is forced against the web 58. If desired, any suitable type of gasket 70 may be inserted between the flange 57' and the web 58 as seen in Figure 11. The plate element 68 is provided at its outer end with a longitudinally extending opening 71, this opening projecting inwardly as far as the sleeve 67 and containing a compression spring 72 which is held in place by a plug 73. The purpose of this spring is to force the sleeve 67 against the threaded shank of the thumb screw and thus to produce friction between the shank and the surrounding members, including the plate 68. There is a stop member 74 projecting upwardly from the web 58 so as to be contacted by the plate 68 as the latter is caused to swing when the thumb screws turn. Assuming that the thumb screw of the clamp illustrated at the lower right hand corner of the compartment 30 (Figure 10) has been rotated clockwise, the plate 68 will also have been rotated clockwise due to the urge of the spring 72 until the lower inner edge of the plate has come into contact with the stop member 74. This is the position shown in Figure 10 and it would normally cause the plate member to be pointed directly toward the center of the bags 50, 51. Further turning of the thumb screw when the plate has reached this position will no longer cause the plate to rotate, but instead will cause the plate to clamp tightly against the flange 57' and thus hold the ring 56' rigidly in position. If it is desired to remove the double bag structure from out of the compartment, it is simply necessary to rotate the thumb screw counterclockwise and eventually the plate 68 will have rotated counterclockwise and assume the position shown by the dot-dash lines as indicated in the lower left hand corner of compartment 30 (Figure 10). As stated hereinbefore, a pair of these clamping devices are provided in compartment 30 to clamp the flange 57' at diametrically opposite positions to the web 58. The compartment 30 is closed at the top by the plate 25 which is secured to the walls thereof in any suitable manner as by screws 75. The pipe 76 projects through an opening in the cover 25 so as to be in communication with the interior of the inner bag 51. This pipe extends from the interior of the filter which is contained in compartment 31 and will be described presently. The main passageway through which the bags 50, 51 are filled with fluid is comprised of an opening 77 in the wall 28 and the opening communicates with the interior of the compartment 31. Thus, the interior of the bag 51 is in communication with the exterior or discharge of the filter contained in compartment 31 through this opening.

Assume that a fluid consisting of a coolant and finely divided foreign material such as metal particles is introduced into the inner bag 51 through the opening 77 or the pipe 76, the fluid flows through the inner and outer bags 51, 50

by the action of gravity and any foreign particles in the fluid are either caught mainly by the inner bag 51 or by the outer bag 50, so that the coolant upon reaching the pump 32 is in an exceptionally clear state.

It is apparent that while the bags 50, 51 are filled with fluid the hydrostatic pressure of the fluid will cause the periphery of the bags to press outwardly against the confining action of the springs 63 and will stretch these springs. However, upon emptying the bags of fluid as when flow through the opening 77 is stopped, the bags are caused to collapse to a shape indicated in Fig. 9 by the compression action of the springs. This radial movement of the bags inwardly and outwardly as determined by the emptying and filling of the bags with fluid tends to prevent any caking of the solids within the interstices between the webs or threads of the cloth or canvas. Any lumps of material are caused to break up when the springs compress the bags and the broken mass immediately drops to the bottom of the bags. Any material which may have collected on the outside of the outer bag is, at the same time, dropped to the bottom of the compartment. The bottom plate 26 of the compartment preferably has a tapered position with the inclination extending downwardly toward the wall 28 so that all the sludge particles exuded by the bags or any broken masses of scum from the outside of the outer bag settle into the lowermost part of the compartment 30 and be received by an opening 78 which extends through a heavy plate member 78' forming a portion of the bottom closure plate. The sludge or semi-liquid mass passes through the opening 78 by gravity into a swarf pump indicated generally at 79 which will be described presently.

The filters 50, 51 in compartment 30 actually constitute the second stage of the filtering system of which the first stage is formed by a filter contained in compartment 31. The first stage filters are quite similar to the second stage filters as described hereinbefore except that they extend in the upward direction which is opposite from the inverted filters of the second stage. It is apparent that in the second filter stage, the coolant is caused to pass through the bags due solely to gravity effects as the upper end of the inner bag is open to the atmosphere.

The manner in which the coolant is strained of its suspended foreign matter is illustrated in Figure 12. This view shows a fragment of one of the outer bags 84, 50 which is preferably made of coarse fabric material so as to leave a completely free opening *a* between each group of adjacent strands. The strands of the fabric are comprised of twisted threads or filaments in the usual manner and therefore have fiber ends extending therefrom in all directions. Thus, extending inwardly of the opening *a* are a large number of fibers or fiber ends indicated at *b*. These fibers strain sediment from the fluid passing through the bag and, further, tend to collect the fine particles together and utilize the natural affinity between such microscopic particles for agglomerating them to a semi-solid mass as at *c*. These masses drop off as the bag expands and contracts due to pressure changes thereon, or are removed from the system through the daily routine change of bags. As the bags are repeatedly cleansed and laundered, the sediment-entrapping fibers become more numerous so that the filtering action is enhanced.

Referring to Figure 4, the compartment which

comprises the walls 23, 25, 28 and 26 is provided with an inwardly extending web 79' near the bottom and which carries an L-shaped ring 80.

The latter may be clamped to the web by a friction clamping device generally indicated at 81 similar to that which was described in connection with Figures 10 and 11. However, the thumb screw 66 is provided with an extremely long shank 82 which terminates near the top cover plate 25 in a knurled knob 83, the function of which is exactly the same as was explained with respect to the thumb screw 66. A pair of clamping devices 81 at diametrically opposite positions may be employed as shown in Figure 10, together with suitable stops 14 so that by rotating the knobs 83 counterclockwise (Figure 10) the L member 80 can be firmly secured to the web 79'. On the other hand, by rotating the knob 83 counterclockwise this member is caused to be loosened from the web so that the filter can be removed from the compartment and inspected or replaced if necessary. The outer bag 84 and the inner bag 85 are similar to those which were described in connection with Figure 8 in which the bag 85 is made of light material in order to collect practically all of the scum obtained from the fluid. This inner bag is also adapted to be removed daily. A pair of springs 63 are sewed in canvas shrouds about the outer bag and, also explained hereinbefore, serve to collapse the middle section of both bags when pressure is removed from the interior of the filter, thus avoiding any tendency for foreign material to cake on the outer surface of the outer bag.

It has been explained that the pipe 45 leading from the pump 33 terminates in a pipe 46 which is received by the inner bag 85. The fluid in flowing from the pipe 46 fills the interior of the bags and the space bounded by the web 79' and the bottom closure member 26 with fluid so that the fluid is finally forced out of both filters into the space determined by the outer periphery of the outer bag 84 and the plates 23, 28, and 25. As the level of the fluid becomes higher than the opening 77, the excess will flow into the compartment 30 and fill the inner bag 51 of the second stage filter with fluid as was explained hereinbefore.

If for any reason, there is any stoppage of the fluid through the filters 84, 85, a back pressure will develop within the bag 85 and it is desirable under these circumstances to permit the fluid within the bag to flow directly into the second stage bag 51. For this purpose, a pipe 86 is provided which extends into the interior of the bag 85 and is in communication through pipes 87, 88 and 89 with the pipe 76 which leads to the second stage filter. The pipe 89 can be made of a transparent plastic material so that by observing whether or not fluid is flowing therethrough into the second stage filter it can be determined as to any excess pressure in the first stage brought about by stoppage of the fluid through the filter bags 84, 85. If there is any considerable flow through the transparent pipe 89, the apparatus is shut down and the bags 85, 84 inspected and if necessary replaced.

It is apparent that the provision of the pipe 86 and the openings 59 all serve to prevent any starving of the circulating pump in the event of partial stoppage of the flow through the filter units. This arrangement insures a positive and unfailing flow of coolant to the grinding wheel under any and all conditions and the inherent

over capacity recirculation prevents filtering efficiency from falling below practical requirements.

As in the case of the compartment 30 the bottom closure member 26 of compartment 31 is given a downwardly extending slope toward the center of the apparatus so that any sludge or other semi-solid mass which drops from the inner filter bag 85 will collect and will flow by gravity through a pipe 90 into the opening 78 which communicates with the sludge or swarf pump 19.

Swarf pump

The sludge or swarf pump 19 (Figure 3) is provided for the purpose of expelling the sludge which had collected at the lowest or deepest part part of the two compartments 30, 31. The details of the pump are shown for the most part in Figures 5, 6 and 7. The pump casing is indicated at 91 and may have a rectangular or round shape, split in two parts at the middle. The parts are bolted together at the ears 92 and flat surfaces are provided at each side of the pump casing in the region of these ears so that the bolts 93 passing through the ears can also secure the pump to the heavy plate 78 forming part of the bottom closure members 26. Within the casing 91 there is a pair of adjacently positioned, longitudinally extending openings 94, 95 separated by a partition 96. These openings are terminated by a plate 97 to which is secured a plunger 98. This plunger may have an annular groove which contains a packing ring 99 and is adapted slidably to move along a circular bore 100 formed in an extension 101 of the casing. The plate 97 is of circular configuration and is also adapted to slide within a circular bore 102 formed within the casing 91. The openings 94, 95 loosely receive rods 103, 104 respectively which are secured at one end to the plate 97 and at the other end are counter-bored to receive a rod 105 of small diameter. There is a flanged plug 106 surrounding each rod 105 so that a completely enclosed space is provided between each rod 103, 104, the partition 96, the plate 97 and the flanged portion of the plug 106. Within each of these spaces there is a compression spring 107 loosely surrounding the rods 103, 104, the purpose of which will be explained presently. A conically shaped sealing member 108 abuts the plugs 106 and loosely fits the rods 105. At the extreme right hand end of each of the rods 105 a flanged sleeve 109 is carried within the casing and slidably fits about the rods 105. This sleeve serves as a support for the rods as they reciprocate during operation to eject the sludge material as will be described presently. The rods 105 are secured to the rods 103, 104 by means of a pair of longitudinally extending bolts 110, the head of which engages the right hand end of each rod 105 and the threads at the other end engage corresponding threads in a counterbored opening within the rods 103, 104. It is apparent that the rods 103, 104 and the rods 105 constitute composite pistons which are adapted to be moved to the left by the pressure exerted at the springs 107 and also adapted to be moved to the right when pressure is exerted at the left hand end of the piston 98. It is evident that these pistons 105 operate in parallel since both of them are secured to the common retaining plate 97 through the rods 103, 104.

To the right of the fixed sleeves 109 there is a thin washer 111 which bears against a so-called star valve 112 held in place by a circular nut 113.

A washer or gasket 115 abuts the facing of the pump casing. The star valve 112 is preferably made of an expansible material such as rubber and is constituted of a series of radially extending slots or grooves, the arrangement being such that when a semi-fluid material is pressed against these slots, the latter are permitted to expand temporarily so as to allow the semi-solid material to pass through the valve into a pipe 116. This pipe is carried on a hub member 117 which is bolted or screwed as indicated at 118 to the valve casing 91. It will be noted in Figure 6 that the plungers 105 are shown in a retracted position due to the absence of pressure in the chamber 100 and due also to the retraction force exerted by the springs 107.

Directly above the ends of the plungers 105 there are two openings 119 passing through the cylinder wall 91 and communicating with the opening 78 in the heavy plate member 38 forming part of the lower cover 26 of the chambers 30, 31. The pipe 116 communicates through a conduit 120 with a pipe 121 which leads to an upstanding compartment 122 provided with a turned over nozzle 123 (Figure 3). This nozzle serves as a discharge outlet for the sludge or other semi-solid material which has been ejected by the pistons 105 of the swarf pump through the conduits 120, 121 and 122. As the sludge collects in the upright pipe 122 a certain quantity of clear liquid may collect on top of the sludge and this liquid can find its way back to compartment 31 through a screen 124 mounted on the wall 23.

In order to apply periodic pressure to the piston 98 and thus to give a reciprocative motion to the plunger 105, a pressure pipe 121' is threaded into the end of the casing extension 101. This pipe is taken through the base 2 (Figure 2) to the main operating pump 125 which provides the necessary fluid pressure for the operating cylinder 126 of the reciprocating work bed 3 of the grinding machine. Consequently, as pressure is intermittently supplied to the cylinder 126 and its contained piston, a corresponding pressure is also applied to the piston 98 causing the plunger 105 to move to the right (Figure 5) and to force any sludge or other semi-solids which had collected in front of the plungers into the grooves of each star valve 112. From thence the semi-solid material is forced into the pipe 116 and finally ejected from the machine at the nozzle 123 into any suitable receptacle (not shown). When pressure is relieved at the back of the piston 98 as when the table 3 is caused to move in a reverse direction and no fluid under pressure is contained within the pipe 121, the plungers 105 are caused to be retracted to the position shown in Figure 6 awaiting the next discharge of sludge to be dropped through the opening 78 (Figure 3).

From the foregoing, it is evident that there has been disclosed an improved form of filtering apparatus for removing solids from lubricating fluids used in connection with metal cutting or metal abrading machines to insure that the lubricant is free from solid matter, even of microscopic size. While I have described my invention from the standpoint of employing two sets of filters connected in series and each set comprising a pair of filter bags, one of which is designed to be removed daily, it will be understood that as many stages of filtering may be employed as is necessary to cleanse the lubricant and also as many bags within each filter set may also be employed if desired. In addition to disclosing

an improved apparatus by which the solids are segregated from the lubricant liquid to a high degree of purity, there is also provision for automatically removing the segregated sludge or semi-solid material from the machine so as to prevent any danger of its return into the lubricating system. If desired, the swarf pump could be manually controlled and manually operated to provide any desired frequency of movement in case the pressure impulses obtained from the main operating pump 125 are not sufficient to keep the passageway 77' entirely clear of sludge.

It will be understood that various modifications and arrangements in structure could be made without departing from the spirit of my invention and, accordingly, I desire to comprehend such modifications and substitutions of equivalents as may be considered to come within the scope of the appended claims.

Having thus fully described my invention, what I claim as new and desire to secure by Letters Patent, is:

1. In a filter; a first compartment having a first filtering unit opening downwardly therein, the open end of said unit being secured to the lower part of the wall of said compartment, a second compartment arranged to receive the overflow from said first compartment and having a second filtering unit opening upwardly therein, the open end of said second unit being secured to the wall of said second compartment beneath the point of entry of overflow fluid from said first compartment, an outlet port withdrawing filtered fluid from said second compartment from around the filtering unit therein, means for supplying fluid to be filtered under pressure to the open side of said first unit, and liquid conducting means connecting the open sides of said units together and with said outlet whereby substantially constant rate of fluid flow obtains regardless of the condition of the filtering medium therein.

2. In a filter; a first compartment having a first filtering unit opening downwardly therein, the open end of said unit being secured to the lower part of the wall of said compartment, a second compartment arranged to receive the overflow from said first compartment and having a second filtering unit opening upwardly therein, the open end of said second unit being secured to the wall of said second compartment beneath the point of entry of overflow fluid from said first compartment, an outlet port withdrawing filtered fluid from said second compartment from around the filtering unit therein, means for supplying fluid to be filtered under pressure to the open side of said first unit, and liquid conducting means connecting the open sides of said units together and with said outlet whereby substantially constant rate of fluid flow obtains regardless of the condition of the filtering medium therein, the liquid conducting means connecting the filter inlets comprising a conduit passing between the inlets and extending above the normal level of the fluid in the first compartment wherein a predetermined resistance to fluid flow through said first unit must be developed to make the liquid conducting effective.

3. In a filter; a first compartment having a first filtering unit opening downwardly therein, the open end of said unit being secured to the lower part of the wall of said compartment, a second compartment arranged to receive the overflow from said first compartment and having a second filtering unit opening upwardly therein, the open end of said second unit being secured to the wall

of said second compartment beneath the point of entry of overflow fluid from said first compartment, an outlet port withdrawing filtered fluid from said second compartment from around the filtering unit therein, means for supplying fluid to be filtered under pressure to the open side of said first unit, and liquid conducting means connecting the open sides of said units together and with said outlet whereby substantially constant rate of fluid flow obtains regardless of the condition of the filtering medium therein, the liquid conducting means connecting the filter inlets comprising a conduit passing between the inlets and extending above the normal level of the fluid in the first compartment wherein a predetermined resistance to fluid flow through said first unit must be developed to make the liquid conducting effective, and the liquid conducting means connecting the inlet of the second unit with said outlet comprising port means in said second unit opening into said second compartment and above the normal level of the fluid in said second unit.

4. In a filter; a first compartment having a mounting ring therein adjacent the bottom, a first filter bag means mounted on said ring and extending upwardly, a second compartment adjacent said first compartment and arranged to receive the overflow therefrom, a mounting ring in said second compartment beneath the point of entry of the overflow fluid, a second filter bag means mounted on said ring and extending downwardly therefrom, a supply pipe opening into said first compartment to supply fluid to be filtered to the inside of said first bag means, an outlet opening from said second compartment to withdraw filtered fluid therefrom from around said second bag means, a conduit passing from the inside of said first bag means to above said second bag means and extending above the normal level of fluid in said first compartment whereby a predetermined resistance to flow through said first bag means will cause bypassing of fluid therearound directly to the inlet of said second bag means, and a plurality of ports around the upper part of said second bag means beneath the mounting ring therefor and above the normal level of fluid therein whereby a predetermined resistance of fluid flow through said second bag means will bypass the fluid from the inlet thereof directly to said outlet.

5. An arrangement as claimed in claim 1 and in combination therewith, a sump for receiving contaminated fluid to be filtered, and a pump operable to pump the fluid from said sump to the open side of said first filtering unit.

6. An arrangement as claimed in claim 1 and in combination therewith, a first sump for receiving the fluid to be filtered, a second sump for receiving filtered fluid from said outlet, and pumping means for conveying the filtered fluid away from said second sump and for conveying the fluid from said first sump to the open side of said first filtering unit.

7. An arrangement as claimed in claim 1 wherein each of the said filtering units comprises an inner filtering member and an outer filtering member spaced therefrom.

8. An arrangement as claimed in claim 1 wherein each of the said filtering units comprises an inner bag of finely woven fabric and an outer bag spaced from the inner bag and comprising a coarsely woven fabric.

OTTO MURRAY SUMMERS.
